UNITED STATES PATENT OFFICE.

GEORGE WESP, OF NEW YORK, N. Y., ASSIGNOR TO ROSENTHAL CHINA CORPORATION, OF NEW YORK, N. Y., A CORPORATION OF NEW YORK.

DESIGN FOR A PLATE OR SIMILAR ARTICLE.

Application filed February 2, 1927. Serial No. 20,584. Term of patent 3½ years.

To all whom it may concern:

Be it known that I, GEORGE WESP, a citizen of Germany, and resident of the borough of Manhattan, city, county, and State of New York, have invented a new, original, and ornamental Design for a Plate or Similar Article, of which the following is a specification, reference being had to the accompanying drawing, forming part thereof, which drawing is a face view of a plate or similar article, illustrating my new design, the dotted lines indicating that the ornament shown at the upper part of the drawing is to be repeated around the plate.

I claim:

The ornamental design for a plate or similar article, as shown and described.

GEORGE WESP.
